UNITED STATES PATENT OFFICE.

JOHN T. AUSTIN, OF HARTFORD, CONNECTICUT, ASSIGNOR TO AUSTIN ORGAN COMPANY, OF HARTFORD, CONNECTICUT, A CORPORATION OF MAINE.

ORGAN-VALVE.

1,100,046.

Specification of Letters Patent. Patented June 16, 1914.

Original application filed February 20, 1905, Serial No. 246,383. Divided and this application filed August 3, 1911. Serial No. 642,196.

To all whom it may concern:

Be it known that I, JOHN T. AUSTIN, a citizen of the United States, residing at Hartford, in the county of Hartford and 5 State of Connecticut, have invented new and useful Improvements in Organ-Valves, of which the following is a specification.

This invention is an improved valve for use in organs, and other instruments where- 10 in simplicity and lightness of construction, ease and rapidity of operation, and flexibility of action are desirable.

Figure 1 is a side view partly in section of portions of an organ embodying this improvement. Fig. 2 is an end view projected from Fig. 1. Fig. 3 is a sectional side view showing the valves of Fig. 1 and their operation more in detail. Fig. 4 is a plan view of one of the valves projected from Fig. 3. 20 Fig. 5 is an end view, projected from Fig. 3, showing in addition a modified form of the valve.

This is a division of my application Serial No. 246,383, filed Feb. 20, 1905, for improvements in organs.

The drawings show the environment of these valves to a sufficient extent to enable their construction and operative relations to be understood.

30 In the embodiment of the present invention herein shown, the valves are appurtenant to the pipe bars 26, which support the organ pipes of the different stops or registers, these pipe bars in this instance forming 35 a part of the upper wall of the ceiling of the wind chest. The pipe ducts 29, through which the air from the wind chest passes to the respective pipes, extend through these pipe bars, which are provided with stop sliders 30 or other suitable devices for drawing the respective stops or registers off and on.

The valves which form the subject matter of the present invention are employed for opening and closing the lower ends of the 45 pipe ducts. Each valve consists of a pallet 75, carried by an integral piece of wire, bent to form the various limbs and members, comprising the eye 77, the pallet arm 76, the hinge or pivot member 78, and the operating 50 or trace arm 79. These parts may be disposed in any desired relation. As herein shown, the two arms stand nearly at right angles to each other, joined by the pivot member 78. The pallet 75 is preferably

formed of a layer of felt 74, with a layer of 55 leather 73 cemented or otherwise secured to each side of it (Fig. 3) and is attached to the pallet arm 76 concentrically with the eye 77 of the pallet arm, which is disposed in a plane suitable for supporting the pallet in 60 proper relation to its duct. Although the round form of eye 77 is generally preferable, it is obvious that triangular or other forms of seat may be employed. For convenience in locating and hinging these valves in their 65 correct position relative to the ducts, the pivot portions or members 78 are seated in saw kerfs or grooves 86 in the under side of the pipe bars 26 at a suitable distance from the ducts to insure proper registration of 70 the pallets with the ducts. In order to enable the pivot portions 78 of the valves to seat securely and yet oscillate freely in the grooves 86, the arms 76 and 79 extend in the same plane from the pivot member until 75 clear of the groove, and then diverge to their desired angular relation; in this instance the grooves, being most conveniently cut in the under faces of the pipe bars, face the general direction of the operating arm 79. 80 Therefore that arm may, as herein shown, extend from the pivot member without any bends, while the pallet arm 76, after extending in the plane of the operating arm 79 far enough to clear the groove, is bent at 85 substantially at right angles to the arm 79 and approximately parallel with the under surface of the pipe bars. Where only a slight rocking motion of the valve is required, as in the present instance, an ordinary saw kerf, wide enough to allow the pivot member to seat freely, will generally be wide enough to allow of the required oscillation. Obviously, where a greater degree of oscillation of the valve is desired, the sides 90 of the groove may be made flaring, either throughout their entire length, or at the location of the arms, to a sufficient extent to allow the desired freedom and amplitude of 95 movement of the valves.

The pivot portion 78 of the valve is retained in place in the groove by buttons or clips 80, which are attached to the under side of the pipe bars 26 by screws 81 or in any other convenient way. These clips may 105 be held against turning edgewise by a wire or spline 82 seated partly in the clip and partly in a saw kerf or groove in the pipe

bar, extending parallel with the groove 86. The lower ends of the arms 79 of the valve levers are bent or otherwise pivotally connected at 88 with the trace or tracker 83, which connects together the valves for the same note in the different stops or registers, as illustrated in Fig. 1. These traces 83, one for each scale note, are connected either directly or indirectly by means of mechanical or pneumatic systems so as to be operated by the keys of a keyboard or the perforations of a note sheet in any well-known way. In the present instance they are shown to be connected by means of a rod 85 with a motor pneumatic 116 attached to a side wall of the wind chest and connected by means of the air passage 113 with any suitable relay device, like those, for example, which are shown in my original application above referred to, of which this is a division. In any case, the endwise movement of the trace 83 opens and closes the ducts 29 in the respective pipe bars, the open and closed positions of the valve being shown in Fig. 3.

25 The pneumatics 116 may be operated either by pressure or vacuum systems. The return movements for closing the valves are preferably effected by means of springs either within the pneumatics themselves or attached to any convenient portions of the traces 83:

This wire construction of the valve has many desirable advantages, especially for pneumatic actions of the character described. 35 Being very light, they respond promptly to the key action. Each lever carries its own pivot or journal member, which may be seated in any suitable groove adjacent to its desired position. Either or both of the wire 40 arms may be easily bent to any desired relation with each other, or to the respective parts with which they are connected; and in the type of organ illustrated therein, their open and accessible disposal enables them to 45 be observed and adjusted by an operator within the wind chest, while the organ is in full operation under normal pressure. The wire also has a certain amount of spring in itself, so that it forms a spring return cushion 50 which materially aids the repetition of the action in rapid passages. This springing property also causes the pallet to leave its seat faster than the normal speed of the action, since the air pressure which holds 55 the pallet against its seat must first be overcome before the pallet will move. The valve arms will therefore yield until this pressure is overcome and the pallet will then be carried away from its seat at an increased rate 60 of speed, due to the combined action of the movement of the trace and the recovery of the spring in the valve arms. The full volume and pressure of air will therefore be admitted to the organ pipe more suddenly than 65 would take place with a more gradual open-

ing of the valve, and the initial quality of the tone will be thereby improved. The spring property of the valve also permits the pressure on the back of the pallet to close the duct opening tightly even if a slight 70 misadjustment of the valve or the action should tend to prevent such closing.

In some instances it is found desirable to employ two ducts leading to the same pipe, instead of employing a single, larger duct, 75 dividing the required duct area between two ducts, thus enabling two smaller valves to be used instead of a single large valve. In such instances the two valves are connected together for simultaneous operation, as illustrated in Fig. 5. The two valves 126 and 127 are provided with separate pallets, each covering a duct as illustrated in the previous figures, the difference being that the operating arm of one valve, in this case 127, is 80 connected with the corresponding arm of the valve 126, so that both are operated by the single trace 128, which thus moves both of the valves 126 and 127 simultaneously.

I claim as my invention:—

1. A valve for organ actions including in an integral piece a pivot member and a pair of arms extending therefrom in the same plane, and thence diverging in different planes.

2. A valve for organ actions including a pivot member, a pair of arms integral with the pivot member, one of said arms being disposed to form a plane seat for a pallet and a pallet attached to the said seat.

3. A valve for organ actions including a pivot member, a pair of arms integral with the pivot member and extending therefrom in the same plane, one of said arms forming a plane pallet seat, and a pallet carried by said seat.

4. The combination, in organ actions, of a grooved pivot seat, and a valve comprising a pivot portion disposed in said seat, and a pair of arms integral with the said pivot portion and extending therefrom in the same plane out of said groove and then diverging in different planes.

5. The combination, in organ actions, of a grooved pivot seat, and a valve comprising a pivot portion disposed in said seat, arms integral with the said pivot portion, and extending therefrom in the same plane, and a clip for retaining the pivot portion in the said groove.

6. The combination, in organ actions, of a grooved pivot seat, a valve comprising a pivot portion disposed in said seat, arms integral with the said pivot portion and extending therefrom in the same plane out of said seat, thence extending in different planes, and a clip for retaining the pivot portion in said seat.

7. The combination, in organ actions, of a grooved pivot seat, a plurality of valves each

having a pivot member disposed in the said groove, and having a plurality of arms each integral with its pivot member, and extending in the same plane out of the said groove.

8. The combination, in organ actions, of a grooved pivot seat and a plurality of valves, each including a pivot member seated in said groove, and having a plurality of arms each integral with its pivot member and extending therefrom out of the groove in the same plane and thence diverging in angular relation.

9. The combination, in organ actions, of a grooved pivot seat and a plurality of valves, each including a pivot portion seated in said groove, and having a plurality of arms each integral with its pivot portion and extending therefrom out of the groove in the same plane, and thence diverging in angular relation, one arm of each valve being provided with a pallet.

10. The combination, in organ actions, of a grooved pivot seat, and a plurality of valves, each including a pivot portion seated in said groove, and having a plurality of arms each integral with the pivot portion of its valve and extending therefrom out of the groove in the same plane, and thence diverging in angular relation, one arm of each valve being provided with a pallet and a trace connected with the other arm.

11. The combination, in organ actions, of

a grooved pivot seat, a plurality of valves each including a pivot member seated in the said groove, and having a plurality of arms each integral with its pivot member, an arm of one valve being connected with the corresponding arm of another valve for simultaneous movement.

12. The combination, in organ actions, of a grooved pivot seat, and a plurality of valves each having a pivot portion, and a pallet arm and an operating arm integral with and disposed in angular relation to the pivot portion, the operating arms of the plurality of valves being connected together for simultaneous movement.

13. The combination, in organ actions, of a plurality of grooved pivot seats, a plurality of valves for the respective seats, each valve including a pivot portion disposed in its pivot seat a pallet arm and an operating arm integral with the said pivot portion, and a trace connecting together the said operating arms of the plurality of valves.

In testimony whereof I have signed my name to this specification in the presence of two subscribing witnesses, this 27th day of July, 1911.

JOHN T. AUSTIN.
